UNITED STATES PATENT OFFICE.

SETH E. PERKINS, OF WATERLOO, IOWA, ASSIGNOR TO PERKINS ELECTRIC DOOR
CONTROL CO., OF WATERLOO, IOWA.

SWITCH.

1,340,403.

Specification of Letters Patent. Patented May 18, 1920.

Application filed April 26, 1919. Serial No. 292,929.

To all whom it may concern:

Be it known that I, SETH E. PERKINS, a citizen of the United States, residing at Waterloo, in the county of Blackhawk and 5 State of Iowa, have invented a new and useful Switch, of which the following is a specification.

This invention relates to improvements in switches, the object of the invention being 10 to provide an improved reversing switch for use in connection with small motors employed in operations in which the direction of motion must be periodically reversed, and which switch is automatic in its action.

15 A further object of the invention is to provide a switch of the character set forth which is comparatively simple in construction, inexpensive to manufacture and highly efficient in operation.

20 With the foregoing and other objects in view, which will appear as the description proceeds, the invention consists in the novel features of construction and combination of parts which will be more fully described 25 hereinafter and particularly pointed out in the claims.

In the drawings accompanying and forming part of this specification,

Figure 1 is a plan view of my improved 30 switch, illustrating the neutral position of the parts; and

35 Figs. 2 and 3 are similar views, on a somewhat smaller scale, showing the parts respectively in the positions they occupy when the lever has been shifted to its extreme positions for reversing the motor.

In all of the figures the circuit is illustrated diagrammatically.

40 The same characters of reference designate the same parts in the different figures of the drawings.

Referring to the drawings, 2 designates 45 a base plate formed of some suitable insulating material. Pivotally mounted approximately at the center of the base plate is a reversing lever 3 having one end thereof projecting beyond the plate as at 4 and adapted to contact with some suitable obstruction that may be placed at the proper 50 point in the travel of the switch whereby to swing the lever on its pivot from one side to the other. The lever 3 is formed of insulating material, such for instance as fiber, and is provided adjacent to each end thereof 55 with a pair of contact points 4, 4' and 5, 5' respectively. A pair of contact members 6,

6' are provided at each end of the base plate, one at each side of the lever 3, a pair of pivoted blades 7, 7' being adapted to establish electrical connection between the contact members 6, 6' respectively, the blades being held in contact-making position by means of helical springs 8, 8', each of which is secured at one end to the base plate 2 and at its opposite end to a clevis 9, 9' pivotally connected respectively to the blades 7, 7'. For the purpose of throwing the blades 7, 7' out of contact with the members 6, 6' at one end of the base board or plate 2, I provide on the inner longitudinal edge of each blade 70 a cam portion 10, and the lever 3 is provided at each side of its pivotal point with a laterally projecting arm 11 adapted to act on the cam portions 10 of the blades 7, 7', as the lever is swung from one side to the other, thereby to force the blades outwardly against the tension of the springs 8, 8'. Each of the blades is provided near one end thereof with a laterally extending pin 12, and a rocking bar 13 is pivotally supported 80 approximately at the center of its length on the base plate 2 and is of such length that its ends will extend beneath the pins 12 when the blades 7, 7' are forced outwardly and will retain the blades in such position. A 85 helical spring 14 is attached at one end to the base plate and at its opposite end to the rocking bar 13 adjacent to one end thereof. Adjacent to the opposite end of the bar 13 is secured a bracket 15 carrying at its lower 90 end a metallic member or weight 16 forming an armature that is adapted to be acted upon by an electromagnet 17 (shown broken away) located at a suitable distance therefrom. By this construction it will be seen 95 that when the magnet is energized the armature 16 will be pulled downwardly, thereby rocking the bar 13 on its pivot against the tension of the spring 14 and causing the ends of the bar to pass from beneath the pins 12, thus permitting the blades 7, 7' to be drawn inwardly under the action of the springs 8, 8' into contact with the contact members 6, 6'. The magnet is in circuit with a suitable battery or other source of energy 100 (not shown), a push button being located at a convenient point for closing such circuit.

The contact members 6, 6' at one end of the base plate are connected by conductors 20, 20' respectively to the poles of a suitable 110 source of energy, indicated at 24, or to a line wire, while a pair of reversing conduc-

tors 23, 23' are connected at one end respectively with the contact points 4, 4' and 5, 5' of the lever 3 and at the other end with conductors 21, 21' respectively, leading to the motor, as shown diagrammatically in the drawings.

The operation of the switch is as follows: The blades 7, 7' being in contact with the contact members 6, 6', with the lever 3 10 swung to one side, for instance to the right as shown in Fig. 3, so that the contact points 4 and 5' at opposite ends and opposite sides of the lever are in contact respectively with the contact members 6 and 6' also at opposite ends and opposite sides of the base plate. Current will now flow from the source through conductor 20, blade 7, reversing wire 23, conductor 21 to the motor, and back through conductor 21', reversing wire 23', 20 conductor 20', back to the source. When the lever is swung over to the opposite position, as shown in Fig. 2, with its contacts 4' and 5 in contact respectively with the contacts 6' and 6 at opposite ends of the base plate, 25 the arms 11 of the lever having meanwhile acted on the cams 10 of the blades 7, 7' and forced such blades out of contact with the contact points 6, 6' at one end of the base plate and the ends of the rocking bar 13 30 having dropped in beneath the pins 12, whereby the circuit is held open and the motor has ceased to operate. If the push button is now operated the electromagnet will be energized, whereupon the ends of the rocking bar 13 will be pulled from beneath the pins 12 and the blades 7, 7' permitted to swing in under the action of the springs 8, 8' into contact with the contact members 6, 6', the lever remaining in the position 35 above described. Current will now flow from the battery through conductor 20, reversing wire 23', conductor 21' to the motor, and back through conductor 21, reversing wire 23, blade 7', conductor 20' back 40 to the source. It will thus be seen that as the lever 3 is alternately swung from left to right the current is directed first to one side of the motor and then to the other, thereby reversing the direction of motion 45 50 of the motor every time the lever is swung from one side to the other.

As an illustration of one of the uses to which the switch herein described may be put may be mentioned the opening and closing of sliding or swinging doors. In such use, the switch is mounted on the door with its end 4 projecting out in such manner that it will come in contact with some suitable obstruction placed at the extreme ends of 55 the path of travel of the door, and it will be readily seen that as the projecting portion 4 of the lever strikes the obstruction the lever is thrown over to the opposite position and in passing from one position to 60 65 the other it throws the blades 7, 7' out of

contact with the contact members 6, 6', whereby the circuit is opened and the motor ceases to operate until the push button is operated to again close the circuit, and when such circuit is closed the motor rotates in the opposite direction, thereby to operate the door in the opposite direction. 70

While I have described in detail the structure herein illustrated, it is to be understood that I do not thereby limit my invention to the precise features of construction shown, as I am aware that many mechanical changes may be made therein without departing from the spirit and scope of the invention as set forth in the appended 75 80 claims.

Having thus described my invention, what I claim is:

1. A device of the class described, comprising a base plate, a lever pivotally mounted thereon, two pair of contact members secured to the base plate at each side of said lever, a pair of blades pivotally mounted on said base plate one in electrical connection with one member of each pair of contact members and adapted to normally maintain the members of the pair in electrical connection, means for permitting the lever to be swung on its pivot, coöperating means carried by the lever and blades 85 for forcing said blades out of contact with one member of each pair of contact members, a laterally extending pin carried by each of said blades, and a bar pivotally mounted on said base plate and adapted to contact with said pins thereby to maintain the blades out of contact with the contact members. 90

2. A device of the class described, comprising a base plate, a lever pivotally mounted thereon, two pair of contact members secured to the base plate at each side of said lever, a pair of blades pivotally mounted on said base plate one in electrical connection with one member of each pair of contact members and adapted to normally maintain the members of the pair in electrical connection, means for permitting the lever to be swung on its pivot, coöperating means carried by the lever and blades for 105 forcing said blades out of contact with one member of each pair of contact blades, a laterally extending pin carried by each of said blades, a bar pivotally mounted on said base plate and adapted to contact with said pins thereby to maintain the blades out of contact with the contact members, and an electromagnet adapted to operate said bar thereby to cause the same to release said blades. 110

3. A device of the class described, comprising a base plate, a lever pivotally mounted thereon, two pair of contact members secured to the base plate at each side of said lever, a pair of blades pivotally 115 120 125

- mounted on said base plate one in electrical connection with one member of each pair of contact members, a spring adapted to normally maintain each of the blades in contact with the other contact member of the pair, means for permitting the lever to be swung on its pivot, a cam formed on each of said blades, and laterally extending arms carried by the lever and adapted to act on said cams thereby to force each of said blades out of contact with one of the contact members.
4. A device of the class described, comprising a base plate, a lever pivotally mounted thereon, two pair of contact members secured to the base plate at each side of said lever, a pair of blades pivotally mounted on said base plate one in electrical connection with one member of each pair of contact members, a spring adapted to normally maintain each of the blades in contact with the other contact member of the pair, means for permitting the lever to be swung on its pivot, coöperating means carried by said lever and blades for forcing said blades out of contact with one member of each pair of contact members, a laterally extending pin carried by each of said blades, a bar pivotally mounted on said base plate and adapted to contact with said pins thereby to maintain the blades out of contact with the contact members, a spring adapted to maintain said bar in contact with said pins, and an electromagnet adapted to operate said bar thereby to cause the same to release said pins.
5. A device of the class described, comprising a base plate, a lever pivoted to the base plate, intermediate the length thereof, a pair of contact members supported on the base plate, adjacent each end of the lever, contact members carried by the lever, means for moving the lever to complete a circuit between the contact members of the lever and contact members on the base member, and electrically controlled means for completing a circuit between the contact members of the base plate, and a source of the electric supply.
6. A device of the class described, comprising a base plate, a lever pivotally mounted thereon, two pair of contact members secured to the base plate at each side of said lever, a pair of blades pivotally mounted on said base plate one in electrical

In testimony that I claim the foregoing as my own, I have hereto affixed my signature in the presence of two witnesses.

SETH E. PERKINS.
